(57) **CLAIM**

I claim the ornamental design for a frog doll, as shown and
described.

DESCRIPTION

FIG. 1 is a rear view of the design;

FIG. 2 is a front view of the design;

FIG. 3 is a left side view of the design;

FIG. 4 is a right side view of the design;

FIG. 5 is a top plain view of the design;

FIG. 6 is a bottom view of the design; and,

FIG. 7 is a side elevational view of the second embodiment
of the design, wherein the feather includes the name of the
design.

The broken lines shown in all views represent stitching.
